US0D1112265S

(12) **United States Design Patent** (10) **Patent No.:** **US D1,112,265 S**
(45) **Date of Patent:** **** Feb. 10, 2026**

(54) **DISPLAY SCREEN OR PORTION THEREOF WITH A GRAPHICAL USER INTERFACE**

(71) Applicant: **PassiveLogic, Inc.**, Holladay, UT (US)

(72) Inventors: **Liujun Du**, Midvale, UT (US); **Troy Aaron Harvey**, Brighton, UT (US)

(73) Assignee: **PassiveLogic, Inc.**, Holladay, UT (US)

(**) Term: **15 Years**

(21) Appl. No.: **29/912,377**

(22) Filed: **Sep. 18, 2023**

(51) **LOC (15) Cl.** **14-04**

(52) **U.S. Cl.**

USPC **D14/485**

(57) **CLAIM**

The ornamental design for a display screen or portion thereof with a graphical user interface, as shown and described.

DESCRIPTION

The FIGURE is a front view of a display screen or portion thereof with a graphical user interface.

The outermost broken lines shown in the FIGURE illustrate portions of the display screen or portion thereof with a graphical user interface that form no part of the claimed design. The other broken lines in the FIGURE show portions of the graphical user interface that form no part of the claimed design.
